UNITED STATES PATENT OFFICE.

CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRIC-CURRENT TRANSFORMER.

1,129,472.

Specification of Letters Patent. Patented Feb. 23, 1915.

Original application filed August 2, 1909, Serial No. 510,854. Divided and this application filed October 8, 1910, Serial No. 586,097. Renewed August 20, 1914. Serial No. 857,772.

To all whom it may concern:

Be it known that I, CHARLES LE G. FORTESCUE, a subject of the King of Great Britain, and a resident of Pittsburgh, in the 5 county of Allegheny and State of Pennsylvania, have invented a new and useful Improvement in Electric-Current Transformers, of which the following is a specification, this application being a division of application, Serial No. 510,854, filed August 10, 1909.

My invention relates to transformers and particularly to the windings and insulation of such transformers as are adapted for very 15 high-voltage service.

The object of my invention is to provide a winding which shall require a very small amount of insulation, relative to the voltage of the transformer, with a view to reducing 20 the space occupied by the insulation and the manufacturing cost of the transformer.

Figure 1 of the accompanying drawings is a partially sectional view of a transformer having its winding divided into four groups 25 of coils which are distributed on the four legs of a substantially square or rectangular core member. Fig. 2 is a view, corresponding to Fig. 1, of a modified structure, in which the high-potential winding is so distributed and the lengths of the coils are so 30 proportioned as to occupy practically the entire space within the core member.

Referring to the drawings, the structure here shown comprises a substantially square 35 or rectangular core member 1, provided with a plurality of similar groups 2, 3, 4 and 5, of low-voltage coils, and groups 6, 7, 8 and 9 of relatively high voltage coils which surround the respective legs 10, 11, 12 and 13 40 of the core member and are separated therefrom by insulating sleeves 14, the high and low-voltage groups being separated from each other by insulating sleeves 15. The low-voltage coils may be connected in any 45 suitable manner. Assuming that a terminal 16 of coil 17 is connected to a high-voltage circuit conductor, circuit is continued from this coil, through coils 18 to 36, inclusive, as clearly shown in Fig. 1 of the drawings. 50 The arrangement shown in Fig. 2 is similar to that of Fig. 1, except that the lengths of the coils are graded according to the available space within the core member. The coils are connected as in Fig. 1, and it

is evident that the coils of highest potential 55 are farthest from the core member, the terminal 37 of the coil 36 being assumed to be connected to ground.

The amount of space occupied by the insulation may be very small, relative to the 60 voltages with which the transformer is intended for use.

Structural modifications may be effected within the spirit and scope of my invention and I do not wish to be limited to the arrangements shown in the drawings.

I claim as my invention:

1. A transformer comprising a substantially square core member and four groups of substantially concentric coils disposed on 70 the respective legs of the core, said coils being connected in a series of which the outer coils of all groups are at one end and the central coils of all groups are at the other end.

2. A transformer comprising a substantially square core member and four similar groups of substantially concentric coils mounted on the respective legs of the core, said coils being connected in series from 80 the coil of largest diameter of one group, through the corresponding coils of the other groups to the next to the largest coil of the first group, through corresponding coils of the other groups to the next adjacent coil 85 of the first group, and so on to the coils of smallest diameter.

3. A transformer comprising a substantially rectangular core member, a winding comprising four groups of concentric coils 90 disposed on the separate legs of the core and graded in length to occupy a maximum amount of space within the core, the coils of the several groups being in a series of which the outer coils of all groups are at one end 95 and the central coils of all groups are at the other end to effect a maximum separation between the high-potential portion of the winding and the core.

4. An electrical device comprising a plural legged core member, of a group of substantially concentric coils upon each core leg, the said coils being connected in a series in which the corresponding coils of the several groups are connected in immediate 105 succession and one coil of each of the other groups is interposed in the series between adjacent coils of the same group.

5. An electrical device comprising a plural legged core member, of a group of coils upon each core leg, the said coils being connected in a series in which the corresponding coils of the several groups are connected in immediate succession and one coil of each of the other groups is interposed in the series between adjacent coils of the same group.

In testimony whereof, I have hereunto subscribed my name this 23rd day of Sept. 10 1910.

CHARLES LE G. FORTESCUE.
